UNITED STATES PATENT OFFICE.

FRANK L. O. WADSWORTH, OF WILLIAMS BAY, WISCONSIN, ASSIGNOR TO
WILLIAM A. BOND, TRUSTEE, OF CHICAGO, ILLINOIS.

TILE STRUCTURE AND TILES THEREFOR.

SPECIFICATION forming part of Letters Patent No. 639,637, dated December 19, 1899.

Application filed April 12, 1898. Renewed May 23, 1899. Serial No. 717,952. (No model.)

To all whom it may concern:

Be it known that I, FRANK L. O. WADSWORTH, a citizen of the United States, residing at Williams Bay, in the county of Walworth and State of Wisconsin, have invented certain new and useful Improvements in Tile Structures and Tiles Therefor, of which the following is a specification.

My invention has for its object to firmly unite tiles or plates in a plane to form panels, platforms, &c.; and to this end I provide the tiles or plates with metallic strips secured to the same at the edges, as fully set forth hereinafter and as illustrated in the accompanying drawings, in which—

Figures 1, 2, 3, and 5 are sectional views of parts of tile structures embodying my improvement, but showing different forms of edge strips. Fig. 4 is an edge view of a tile, 20 showing the edge strip differently arranged; and Fig. 6 is a detached view of the edge strip shown in connection with the tiles in Fig. 5.

The tiles or plates N N may be of the forms and materials which it is desired to assemble 25 and connect to form panels, platforms, &c., and, as shown in Fig. 1 are the prismatic panels of an illuminating structure. In connecting such tiles they have frequently been arranged in a plane, with their edges slightly separated, 30 and a framework has been formed by pouring molten metal into the intervening spaces, but this has proved unsatisfactory from the lack of adhesion between the framework and the tiles. To overcome this defect, I embed 35 in the edges of each tile a metallic strip a of any suitable character. These strips may be of different forms. As shown in Fig. 1 they are flat strips with beveled edges, which prevent the lateral detachment of the strips.

40 The like result is secured by embedding a round strip or wire, Fig. 2, to more than half its thickness, or the flat strip may be secured or anchored by bending back tongue portions 33, Fig. 6, which when embedded in the body 45 of the tile, Fig. 5, in molding the latter, secure a firm hold. The tiles, with the edge strips of any of the described or suitable forms, are assembled in a flat plane, with their edges slightly separated, and the connecting-

50 frame A is cast or formed by electrodeposit between the separated edges, the metal of

the frame A becoming practically welded or soldered to the strips a, and thereby firmly uniting the tiles together.

The strips a may fully cover the faces of the 55 tiles, as in Fig. 5, or only partially cover the same, as in other figures, and serve in any case to strengthen the tile and prevent fracture.

All the tiles need not be alike. For instance, some may have a single strip and others 60 double strips, as in Fig. 3. The strips may also be zigzag, as in Fig. 4.

An important feature in the above construction applicable to blocks, plates, &c., for various purposes is the partial embedding of 65 the metallic strips in the faces of the glass. The strips thus strengthen the glass, and being partially exposed can contract or expand without fracturing the glass.

Without limiting myself to the precise construction described and shown, I claim—

1. A tile structure consisting of tiles having metallic strips a, at the edges and united by intervening metallic strips A, substantially as described.

2. A tile structure consisting of tiles having metallic strips a, embedded in the edge portions thereof and intervening metallic strips A, united to the strips a, substantially as described.

3. A tile provided with metallic strips a arranged permanently at the edges and forming part of the tile, for the purpose set forth.

4. A tile provided with metallic strips permanently embedded in the edge portions 85 thereof, substantially as described.

5. A tile having metallic strips secured permanently to the same and covering the edges and forming a part thereof, substantially as and for the purpose set forth.

6. The combination with a non-metallic plate or block, of metallic strips embedded in and partially exposed at the face of the plate or block, substantially as set forth.

In testimony whereof I have signed my 95 name to this specification in the presence of two subscribing witnesses.

FRANK L. O. WADSWORTH.
